UNITED STATES PATENT OFFICE

2,620,372

TUBE HOLDER AND LIGHTING SYSTEM

Edwin G. Goddard, Lombard, Ill.

Application October 11, 1948, Serial No. 53,771

5 Claims. (Cl. 173—328)

1

This invention relates to an improved tube holder for fluorescent lamps or the like, and to an improved safety lighting system embodying such tube holder.

This application is an improvement on the invention of my application Serial No. 631,679 filed November 29, 1945, now abandoned.

That application relates to a safety lighting system which is relatively foolproof. More particularly, means are provided for automatically breaking the primary circuit of the energizing transformer when any one of several tubes is removed from the system. Thus all of the secondary circuits go dead and there is no danger of shock to the operator. Such a system is particularly well adapted for use in connection with gaseous induction tubes of the type which require a starting voltage several times in excess of the operating voltage. For instance, the so-called quick start tube in use today requires a starting voltage of from 450 to 1,000 volts which may be considered dangerous from the shock standpoint to the average user.

It is an object of my invention to provide a lighting system in which the terminals of the tubes are themselves utilized as certain ones of a plurality of conducting elements necessary to establish a series circuit with the primary of the transformer so that the removal of any one tube will automatically deenergize the transformer.

It is a further object of the present invention to provide a tube holder in which the tube terminal contacting elements themselves, in combination with the tube terminals, constitute all of the conductors necessary to establish the series circuit for the primary of the transformer. Thus, separate circuit breaking means are eliminated, resulting in a tube holder of more simple design than that disclosed in my prior application, and one which can be manufactured at less cost.

Other objects, features and advantages will become apparent as this description proceeds.

With respect to the drawings which illustrate a preferred embodiment of my invention and in which like reference numerals represent like parts:

Fig. 1 is a perspective view showing the relationship of the tubes and tube holders;

Fig. 2 is an elevation of a tube holder embodying my invention, the cover being removed;

Fig. 3 is an end elevation of the tube holder shown in Fig. 2, the cover being shown in dotted lines;

Fig. 4 is an enlarged detailed sectional view taken along line 4—4 of Fig. 2;

2

Fig. 5 is a bottom plan view of the tube holder and tube assembly, portions being broken away;

Fig. 6 is a wiring diagram of the lighting system embodying my invention;

Fig. 7 is a diagram showing a modification; and

Figs. 8, 9, 10 and 11 are views showing a further modification.

The reference numeral 10 designates generally a plurality of fluorescent tubes which are mounted in side by side relationship in tube holders 11 and 12. The tubes are individually designated by the reference numerals 10a, 10b, 10c, and 10d, respectively.

The tube holder 11 comprises a base 13 and a cover 14 as shown in Fig. 3, the cover being shown in dotted lines. The base 13 is made from sheet metal having turned up edges which are adapted to engage the edges of the cover 14, which is generally box-shaped. One of the side walls of the cover is provided with a series of apertures 20 through which the tubes 10 may be inserted.

A plate 17 of suitable insulating material depends vertically from the base 13 and is secured thereto by means of brackets 18. The plate is provided with a series of apertures 19 which are in alignment with the apertures 20 but which may be considerably smaller since they receive only the tube terminals 23 which are of considerably smaller diameter than the tubes themselves.

A plurality of resilient contact strips are secured to the rear surface of the plate 17, these strips being designated by the reference numerals 21 to 25 inclusive.

The strips are arranged as shown in Fig. 2 so that the end portions of two different strips overlie each one of the apertures 19. The strips 22, 23 and 24 can be termed "double strips" since they are secured to the plate 17 at their midpoint by means of rivets 26, the two free ends of these tube strips overlying portions of adjacent apertures. In other words, the double strips serve to provide a connection between the tube terminals which are received in adjacent apertures. The strips 21 and 25 which overlie a portion of the end apertures can be termed "single strips" since they have only one free end, the other end being anchored to the plate 17 by means of rivets 26. A terminal 27 is secured to strip 21 in electrical conducting relationship and a terminal 28 is secured to strip 25 in electrical conducting relationship. The rivets 26 which anchor the strips 21 and 25 to the plate 17 also pass through the terminals 27 and 28, as shown in Fig. 4. The terminals 27

and 28 include a screw by means of which conductors may be secured thereto.

As shown in Fig. 5 the tube terminals 29 are in the form of pins which are adapted to project into the apertures 19 and engage both of the resilient strips which overlie portions of each aperture. When the parts are in operative position as shown in Fig. 5 the resilient strips will be displaced backwardly to a certain extent, although the showing in Fig. 5 may be exaggerated in this respect for purposes of illustration. Thus, the tube terminals 29 serve as bridging members which bridge the gaps between the end portions of adjacent resilient strips and serve to connect all of said resilient strips in series circuit with each other. When all of the tubes are in operative position, a circuit is established between the terminals 27 and 28.

The tube holder 12 is provided with an insulating plate 50 which is suitably supported from the base 15, as shown in Fig. 5. On the base 50 are mounted a plurality of coiled contact springs 30 which are adapted to be extended rearwardly when engaged by the terminal of a tube to form a socket for resiliently supporting the tube. The contact springs 30 also engage the tube terminals 29 in electrically conducting relationship, and each one of the contact springs is provided with a terminal 31 to which a conductor may be secured. In Fig. 5, tube 10d is broken off for illustrative purposes, showing its respective spring 30 in collapsed position and exposing the terminal 31. The side wall of the cover 15 is provided with a series of apertures 32 with which the contact springs 30 are aligned.

In operation, one end of a tube 10 is first inserted into the apertures 32 of the tube holder 12 and is caused to engage the spring 30 and extend the same sufficiently so that the other end of the tube will clear the tube holder 11. Then the tube terminal 29 is guided through the corresponding aperture 20 in the tube holder 11 and into the aperture 17 at which point it engages the pair of the resilient contact strips and bridges the gap between them. During this time the tension on the contact springs 30 is somewhat relaxed, as the opposite end of the tube is moved into the holder 11. The contact springs 30 should be disposed sufficiently close to the apertured wall of the tube holder 12 as to permit distension of the spring so as to enable the opposite end of the tube to clear the holder 11. The series circuit between terminals 27 and 28 will remain broken until the last tube is in place, with the result that the whole system is dead until the final step is taken.

The manner in which the parts are connected into circuit with suitable energizing means is shown diagrammatically in Fig. 6.

The reference numerals 35 and 36 designate power lines connected with a suitable source of power. The reference numerals 37 and 38 designate the primary and secondary coils, respectively, of one autotransformer and the reference numerals 39 and 40 designate the primary and secondary coils, respectively, of another autotransformer. The power line 35 is connected to taps between the primary and secondary coils of each of the two autotransformers, by leads 41 and 42. Leads 43 and 44 connect the other side of the primary coils 37 and 39 with terminal 27 of the tube holder 11. Terminal 34 of the tube holder 28 is connected to the power line 36.

It will be seen that the circuit through the primaries 37 and 39 will be opened by the re-

moval of a single tube 10, thereby deenergizing the primary circuit. Tubes 10a and 10b are connected in parallel with the secondary circuit of one autotransformer which includes coils 37, 38 and suitable inductances 47a and 47b. The condenser 48b is provided for the tube 10b to reduce stroboscopic effect. The secondary circuit for tubes 10c and 10d includes coils 39 and 40, and inductances 47c and 47d. A condenser 48d is also provided in series with tube 10d.

In this arrangement of the parts it will be seen that not only is the secondary circuit for a particular tube broken when that tube is removed, but the primary circuit for both autotransformers is also broken, thereby deenergizing all of the tubes. This is because the tube terminals 29 serve to bridge the gaps between adjacent resilient contact strips, and as soon as one tube is removed, the series contact between the elements will be broken.

It will be understood that a separate conductor is provided for each of the coiled contact springs 30 in holder 12.

For the purposes of this invention, it is immaterial whether only one of the secondary circuits of each transformer is provided with a condenser or whether both secondary circuits are. Furthermore, the inductances 47 may be eliminated provided that sufficient impedance is present in the combination transformer and condenser means. Also, it will be understood that instead of the autotransformers shown in Fig. 6, insulated transformers may be used, providing that a portion of the secondary circuit also comprises a portion of the primary circuit, the common portion including the resilient contact members and tube terminals referred to above.

The operation of the circuit as a whole, and a description of the steps involved in inserting and removing the tubes has been given above in connection with the description of the various elements. It will be seen that the lighting system above described is practically foolproof. Furthermore, the covers of the holders do not need to be removed to permit the insertion or removal of a tube.

It is obvious that tubes having other types of terminals may be utilized in the tube holder and system above described. The size of the apertures 19 may be varied to receive the ferrule type tube terminal shown in my earlier application. Also, the present invention may be applied to the two pin type of terminal either with or without a shorted filament, one of the terminal engaging members engaging one of the pins and the other of the members engaging the other of the pins. Thus, the two pins of the terminal serve to bridge the gap between the two terminal engaging members.

Such an arrangement is shown in Fig. 7 in which plate 17 is provided with a series of pairs of apertures 51 and 52, respectively, for receiving pins 53 and 54 of tube terminals 55. In this arrangement, a double resilient strip 56 is provided for engaging pins 53 and 54 of adjacent tubes. Resilient contact strips 57 and 58 can either be single strips provided with suitable terminals or can represent portions of double strips, the opposite ends of which are engaged by pins of adjacent tube terminals in much the same manner as described in connection with the preceding figures.

Furthermore, instead of providing tube contacting members in the form of resilient contact strips which are displaced backwardly when

engaged by a tube terminal, contact members may be provided which will be displaced in a lateral direction when engaged by the tube terminals, the tube terminal thus serving to bridge the gap between the two contact members as well as being connected into its respective secondary circuits. Such an arrangement is shown in Figs. 8, 9, 10 and 11 which represent a modified form of tube holder. Two insulating members 60 and 61 are secured to each other in perpendicular relationship, the insulating member 60 being disk-shaped and being provided with an aperture 62. The member 60 is provided with an aperture 62. The member 61 is provided with a cut-away portion 63 to permit the insertion of a tube terminal through aperture 62. Resilient contact strips 64 and 65 having suitable terminals 66 and 67, respectively, are suitably secured to the insulating member 61 in such a manner that they will engage the opposite sides of a tube terminal and be displaced laterally by the tube terminal as it is inserted in aperture 62. Thus, the gap between the contact members 64 and 65 is bridged by the tube terminal. Any number of such tube holders may be mounted in a suitable housing, with the terminals of adjacent holders connected to each other so as to provide a series circuit which will be broken by the removal of any one tube.

It will be understood that the term "tube" as used herein covers the term "lamp."

Although preferred embodiments of my invention have been shown and described herein, it will be understood that various modifications and changes may be made without departing from the spirit of this invention. The foregoing description and the drawings are illustrative only and the invention is to be limited only by the appended claims.

I claim:

1. A tube holder for supporting one end of a plurality of lamp tubes in side by side relationship comprising a tube supporting member formed of insulating material and having a series of apertures disposed in side by side relationship for receiving the terminals of said tubes, a plurality of pairs of flat leaf springs disposed in a plane parallel to the rear surface of said tube supporting member, means securing a portion of each leaf spring to the rear surface of said tube supporting member so that the free end portions of each pair of leaf springs will overlie each aperture of said series whereby each tube terminal will be engaged by two of said leaf springs, said free end portions being spaced from each other, the free end portion of one leaf spring of each pair being in direct electrical connection with the free end portion of one leaf spring of an adjacent pair, whereby a series connection will be established through the spaced end portions of said leaf springs and through the tube terminals when a tube terminal is received in each of said apertures.

2. A tube holder for supporting one end of a plurality of lamp tubes in side by side relationship comprising a plate formed of insulating material and having a series of apertures disposed in side by side relationship for receiving the terminals of said tubes, a plurality of substantially flat resilient contact strips spaced from each other and disposed in a plane parallel to the plane of said plate and anchored to said plate and arranged so that each aperture will be partially covered by the free end portions of two of said contact strips, the two free end por-

tions overlying an aperture being spaced from each other whereby each tube terminal will be engaged by two of said resilient contact strips, the free end portion of one of the two contact strips overlying each opening being in direct electrical connection with the free end portion of one of the contact strips overlying an adjacent opening whereby a series connection will be established through the spaced free end portions of said contact strips and through the tube terminals when a tube terminal is received in each of said apertures.

3. A tube holder for supporting one end of a plurality of lamp tubes in side by side relationship comprising a plate formed of insulating material and having a series of apertures disposed in side by side relationship for receiving the terminals of said tubes, a plurality of substantially flat resilient contact strips spaced from each other and disposed in a plane parallel to the plane of said plate and anchored to said plate and arranged so that each aperture will be partially covered by the end portions of two of said contact strips, said two end portions being laterally spaced from each other whereby each tube terminal will be engaged by two of said resilient contact strips, certain of said resilient contact strips being so positioned as to partially cover adjacent openings and being anchored at their intermediate portions, and two of said resilient contact strips which partially cover the end apertures of said series being provided with terminals whereby a series connection will be established through said resilient contact strips and through the tube terminals when a tube is received in each of said apertures.

4. A tube holder for supporting one end of a series of lamp tubes in side by side relationship comprising a tube supporting member formed of insulating material and having a plurality of apertures for receiving the terminals of said tubes, and a plurality of terminal engaging elements arranged in pairs which are spaced from each other and resiliently mounted on said tube supporting member behind said apertures whereby each tube terminal will be engaged by two of said elements which are spaced from each other, one element of each pair being in direct electrical connection with one element of an adjacent pair, whereby a series connection will be established through said spaced terminal engaging elements and through the tube terminals when all the tubes of said series are received in said apertures, said terminal engaging elements being in the form of substantially flat leaf springs which are disposed in a plane parallel to the rear surface of said tube supporting member, the free end portions of said leaf springs being adapted to be displaced rearwardly when engaged by a tube terminal.

5. A tube holder for supporting one end of a series of lamp tubes in side by side relationship comprising a plate formed of insulating material and having a series of apertures disposed in side by side relationship for receiving the terminals of said tubes, and a plurality of substantially flat resilient contact strips spaced from each other and disposed in a plane parallel to the plane of said plate and anchored to said plate and arranged so that each tube terminal will be engaged by two of said spaced resilient contact strips, all but two of said resilient contact strips being so positioned as to be engaged by the terminals of adjacent tubes and being anchored at their intermediate portions, and the remain-

ing two of said resilient contact strips engaging the terminals of the end tubes of said series whereby a series connection will be established through said spaced resilient contact strips and through the tube terminals when all the tubes of said series are received in said apertures.

EDWIN G. GODDARD.
